CIGAR MACHINE MOISTENING MECHANISM

Sigurd Clausen, Brooklyn, N. Y., assignor to International Cigar Machinery Company, a corporation of New Jersey

Application February 9, 1942, Serial No. 430,128

3 Claims. (Cl. 131—138)

This invention relates to cigar machines, more particularly to mechanism for moistening the ends of the cigar bunches delivered from the softening mechanism, prior to delivery of the bunches to the crimping or shaping mechanism. Heretofore the bunch ends were moistened, as shown in the Halstead Patent 1,765,831, by pendant wicks suspended in the path of the bunch as it was carried by the transfer from the softening mechanism to the crimping mechanism, wherefore the moisture on the bunch ends was transferred to the crimping jaws of the crimping mechanism. The moisture so applied to the crimpler jaws helps to keep the operating faces thereof free of tobacco particles which may escape from the ends of the bunch and otherwise would accumulate and form hard lumps on the jaw faces due to the tobacco juices pressed out of the bunch during the crimping operation.

The main object of my invention is to provide novel devices for simultaneously locating and moistening the ends of a bunch delivered from the bunch softening means, prior to transfer of the bunch to the crimping mechanism. The construction of the locators shown in the above-mentioned patent, which is in extensive use on cigar machines, does not permit of rotation of the locators, whereas my locators revolve oppositely in a direction to wipe down the ends of the binder which is spirally wound about the bunch charge. Moreover, moisture is transferred from moisture wells suspended from the locators by endless members, such as bead chains, mounted on the exterior of the locators and driven therefrom to carry moisture up from the wells. The locators are perforated to permit the moisture transferred by the bead chains to reach the ends of the bunch engaged by the locator. However, in the case of cigars which have straight tuck ends, it is unnecessary to moisten the tuck end of the cigar bunch; since with this shape of the cigar bunch there is not enough compression thereof in the crimpler jaws to squeeze out enough tobacco juice to cause the particles of tobacco escaping from the tuck end of the bunch to form hard lumps of tobacco on the operating faces of the crimpler jaws.

In the accompanying drawings:

Fig. 1 is a front elevation, partly in section, of the improved moistening mechanism associated with the softening mechanism and the bunch transfer for removing the softened bunch;

Fig. 2 is an end elevation of the moistening and softening mechanism and the bunch transfer viewed from the line 2—2 of Fig. 1; and

Fig. 3 is an enlarged sectional view through one of the moisture wells showing the bead chain suspended in the well from the overlying locator.

With reference to Figs. 1 and 2, the cigar bunch B is delivered from the bunch rolling apron to the softening mechanism at a point A by a bunch transfer (not shown) having a construction similar to that shown in the co-pending application of H. H. Wheeler, S. N. 234,001, filed October 8, 1938, and having parts or fingers which hold the bunch and enter slots 5 in the concave 1 and deposit the bunch between the concave and the drum 10. The bunch is rolled along the concave and manipulated and deposited at the position B on cradle 14 by the rotation of the drum which is mounted on a shaft 51 driven in a counter-clockwise direction by mechanism hereinafter described. The concave is supported from stationary bars 12 held in the housing 13. On each of the bars 12 is clamped a support 15 to which resilient members, such as wires 16, are clamped by a plate 17 secured to the support by a cap screw 18. The inner lugs 19 of the concave 1 have holes through which the bars 12 pass, and the ends of the wires 16 are clamped to the inner and outer lugs 19 by plates 20 secured to the latter by cap screws 21. The cradle 14 on which the bunch B is deposited consists of curved arms 23 mounted on a member 24 fastened in and projecting from housing 13. The bunch B resting in cradle 14 is then engaged by constantly rotating locating and moistening heads 26 and 26a, these heads being moved simultaneously in a horizontal direction towards the ends 35 of bunch B, as will be presently described. Endless bead chains 27 each supported in a circumferential groove 28 cut in heads 26 and 26a have their lower portions submerged in water W held in moisture wells 29 and are thereby constantly driven to carry water up to heads 26 and 26a by chains 27, which flows through holes 30 into the conical cups 31 formed in the locator heads which engage the ends of bunch B. Each of the moisture wells 29 has a flange 33 mounted on the stem of its respective locator head, each of said stems being threaded into the hub 35 of gear 38 and shaft 36 respectively. Each of said stems revolves freely within the flanges 33, the locator heads being screwed into the hub 35 and shaft 36 respectively, to positions where there is sufficient play between the shoulders thereof adjacent the flanges 33 to permit their stems to revolve freely in said flanges. As shown in Fig. 1, the stem 34 is threaded into the hub 35, and the stem of the locator 26a is similarly

threaded into its shaft 36 which is supported by a sleeve 37 slidably mounted in housing 13. The hub 35 of gear 38 revolves in housing 43 and gear 38 is driven through gears 39 and 40 from a gear 41. The gears 39 and 40 are mounted on studs 42 carried by the gear housing 43 which is clamped on a sleeve 44 slidably mounted in housing 13. Within the sleeve 44 revolves a shaft 46 which carries the gear 41.

The bunch locating action of heads 26 and 26a, that is the horizontal reciprocating motion of the same, is achieved by mechanism which will now be described. A cam 47 has a cam track 48 engaging with a cam roller 49 pivoted to an operating block 50 which is releasably secured to the sleeve 44. Operating block 50 is provided with a track 51 slidably engaging with a shoe 52 pivoted to one end of a double lever 53, the other end of said lever being pivoted to a shoe 54 slidably engaging with a track 55 of an operating block 56 adjustably secured to sleeve 37 which carries the shaft 36 on which the locating head 26a is mounted. The double lever 53 is pivoted to a stud 57a held by a bearing lug of housing 13. The blocks 50 and 56 may be clamped or otherwise secured to their respective sleeves 44 and 37, so that upon releasing the same from the sleeves the latter may be adjusted to position the locators to properly engage the ends of different lengths of bunches.

On shaft 46, which drives the head 26, is fastened a gear 58 meshing with a pinion 59 which in turn is driven by a gear 60 loosely mounted on a stud 61 fastened in the portion of the housing behind cam 47. The gear 60 is securely attached to gear 62 which is also loosely mounted on stud 61. Gear 62 is driven from a gear 63 fastened to the cam 47. The shaft 64 of cam 47 is mounted in bearing lugs on the bottom of housing 13 and gear 63 is driven from the main drive of the machine. On shaft 36, which revolves head 26a, is fastened a gear 65 meshing with a pinion 65a mounted on a stud 66 fastened in a suitable bearing lug of housing 13. Gear 65a meshes with gear 67 on the shaft 57 of drum 10, and gear 67 also meshes with gear 59 whereby shaft 36 is constantly driven. The bunch B, after moistening heads 26 and 26a have moved in and located and moistened its ends, is held between the locators waiting to be moved to its next position. This is accomplished by a bunch transfer having a pair of fingers 69 and 70, the finger 69 having its upper end 71 secured on shaft 72. The finger 69 is bifurcated and pivoted on finger 70, and a latch 73 pivoted on finger 70 has a shoulder resting on a strip 74 connecting the legs of fingers 69. A tension spring 76 connected to a post 78 on finger 69, and anchored to a post 80 on latch 73, holds the shoulder of the latch down against the plate 74 to maintain the fingers 69 and 70 in open position to admit the bunch B therebetween when they descend to a position in which they encompass the bunch, finger 69 passing through a slot in member 24.

The shaft 72 is supported in and protrudes from the outer end of a hollow arm 75 wherein it is free to revolve, the inner end of arm 75 being fastened to shaft 71. A bevel gear on the inner end of shaft 72 meshes with a bevel gear on one end of a shaft (not shown) supported within and free to revolve within the arm 75 and having a bevel gear (not shown) at its other end meshing with a bevel gear on shaft 77, whereby the fingers are maintained in an upright position as they descend with arm 75 to pick up the bunch B.

The shaft 77 is turned to and fro through a gear (not shown) mounted thereon and meshing with a rack (not shown) connected to and operated from a cam lever (not shown) actuated by the plate cam 80 on shaft 64. When the fingers reach the bunch B, the projecting end of the latch 73 is engaged and tripped by the adjustable stop screw 82 on bar 24, and the spring closes the fingers 69 and 70 on the bunch B to carry it in a clockwise direction to bunch shaping or crimping mechanism (not shown).

The shaft 84 shown protruding from the housing 13 is slidably mounted in the latter and carries a pair of arms (not shown) both of which may be yieldingly mounted on the shaft 84, as described in the above-mentioned Wheeler application. On the outer ends of these arms are mounted relatively yieldable fingers between which is received the bunch from the rolling apron and from between which it is deposited at the point A. The shaft 84 has a gear segment (not shown) meshing with a gear segment on a cam lever (not shown) operated by cam 80, and shaft 84 also has a cam block fastened thereon and provided with a circumferential cam track engaged by a stationary roller to displace the shaft 84 axially as it carries the bunch from the rolling apron to the softening mechanism. Since the construction of the mechanism for oscillating and displacing axially the shaft 84, as well as the construction of the arms on the shaft 84 and the fingers supported thereon is similar to that shown in the above-mentioned Wheeler application, further description is deemed unnecessary.

It will be understood that other types of endless members may be employed for transporting moisture from the wells to the locators, such as "Universal double jointed chain."

The construction and operation of the bunch transfer for transporting the located and moistened bunch to the crimping mechanism is no part of this invention, but forms the subject matter of the co-pending application, J. F. Halstead, Serial No. 431,197 filed February 17, 1942. The bunch locating mechanism also forms the subject matter of said Halstead application.

What is claimed is:

1. In a cigar machine, the combination with a set of spaced opposed locator cups, of a support for a cigar bunch, means for oppositely moving said locator cups toward each other to engage the interior of the cups with the ends of a bunch on said support, moisture wells supported from each locator movable therewith, endless members suspended from said locators and dipping into said wells, and mechanism for rotating said locators while they engage the bunch ends, said locators having external annular grooves wherein said endless members are disposed, and perforations extending from the interior of said cups into communication with said grooves, whereby rotation of said locators will drive said members to cause them to transfer moisture from said wells to said grooves for conduction through said perforations to the ends of the bunch with which the locators are engaged.

2. In a cigar machine, the combination with a set of spaced opposed locator cups, of a support for a cigar bunch, means for oppositely moving said locator cups toward each other to engage the interior of the cups with the ends of a bunch on said support, moisture wells supported from each locator movable therewith, endless members suspended from said locators and dipping into

said wells, and mechanism for rotating said locators while they engage the bunch ends, said locators having external annular grooves wherein said endless members are disposed, and perforations extending from the interior of said cups into communication with said grooves, whereby rotation of said locators will drive said members to cause them to transfer moisture from said wells to said grooves for conduction through said perforations to the ends of the bunch with which the locators are engaged, said endless members consisting of bead chains.

3. In a cigar machine, the combination with a set of spaced locator cups, of a support for a cigar bunch, means for oppositely moving said locator cups toward each other to engage the interior of the cups with the ends of a bunch on

5 said support, a moisture well supported from the locator which is arranged to engage the head end of the bunch on said support, said well being movable with said head locator, an endless member supported from said head locator and dipping into said well, and mechanism for rotating said locators while they engage the bunch ends, said head locator having an external annular groove wherein said endless member is disposed and perforations extending from the interior of the head locator cup into communication with said groove, whereby rotation of said head locator will drive said member to cause it to transfer moisture from said well to said groove for conduction through 10 said perforations to the head end of the bunch with which the head locator is engaged.
